UNITED STATES PATENT OFFICE.

GEORGE M. SMITH, OF CANTON, OHIO, ASSIGNOR TO A. O. SMITH CORPORATION, OF MILWAUKEE, WISCONSIN, A CORPORATION OF NEW YORK.

DRAWING-PRESS.

1,373,571.

Specification of Letters Patent.

Patented Apr. 5, 1921.

Application filed May 24, 1920. Serial No. 383,964.

To all whom it may concern:

Be it known that I, GEORGE M. SMITH, a citizen of the United States, and a resident of the city of Canton, county of Stark, and 5 State of Ohio, have invented a certain new and useful Improvement in Drawing-Presses, (Case #148;) and I do declare the following to be a full, clear, and exact description thereof, such as will enable others 10 skilled in the art to which the invention pertains to make and use the same, reference being had to the accompanying drawing as illustrating one construction in which the invention has been embodied.

15 The invention relates to presses which are designed to draw metal plates or blanks into flanged bars.

The larger uses of such presses involve their employment in the production of side 20 bars for automobile frames, which side bars as is well known, are formed with a vertical web with flanges standing perpendicular to the plane of the web. In some types of automobiles, the side bars have a considerable 25 length, and the practical production of such lengthy bars necessitates the erection of presses of extreme dimensions. The output of presses of the type ordinarily used in this work is restricted, by reason of the time required to feed the blanks into the press and withdraw the flanged bars after the drawing 30 operation has been completed. The actual time consumed in performing the drawing operation is but a fraction of the time cycle required for one complete operation of the press.

The presses employed for drawing lengthy flanged or channel bars from sheet metal, are usually of the type known as end feed. 40 Such presses are provided with a bed supporting the matrix at or near the longitudinal center line of the press, and a reciprocating head which carries the complementary die member or punch. Straining rods arranged and fixed in parallel rows at each side of the press, serve to tie the crown of the press to the bed thereof, the reciprocating punch carrying head being guided by the said straining rods. The latter resist 45 the expansive force generated in the operation of the eccentrics, which are used to impart motion to the reciprocating punch carrying head. In the type of drawing press just described, the blanks to be drawn are

fed into the press at one end thereof, and 55 after being shaped by the die members of the press, are withdrawn at the other end thereof. This operation of thus feeding the blank and withdrawing the flanged bar, requires a considerable amount of time, and 60 necessitates the complete arrest of the motion of the press to enable the flanged bar to be withdrawn, and another blank to be inserted and correctly positioned between the die members. The press is then thrown into 65 operation, and the cycle of intermitting movement is repeated, as described. The operations of feeding the blank, correctly positioning the same with reference to the die members of the press, and withdrawing 70 the flanged bar are manually performed in most presses, and the output of the press is necessarily dependent upon the activity and skill of the crew of pressmen. The time required for manually shifting the clutch 75 into and out of operation is but a momentary one.

I have referred to the straining rods as being arranged in parallel rows at the side of the press. Each of such rows is composed 80 of a plurality of straining rods, usually five or six or more, and these are spaced throughout the length of the press so as to secure, as far as possible, an even distribution of the pressure exerted in the drawing operation, and confine the expansive pressure of the press within the limits of the elasticity 85 of its construction. The employment of the several straining rods in each row, as described, renders the press inaccessible from 90 the sides for the purpose of feeding the blanks thereto and removing the flanged bars therefrom, and necessitates such operations to be performed at the ends of the press.

Drawing presses open at the sides and designed to permit the feeding of the blanks and withdrawal of the side bars have been used, but in such constructions it has been necessary to construct the crown of the press 100 as well as the base thereof, in massive proportions, and to tie the crown to the base by means of straining rods of such diameter and tensile strength as to successfully resist the expansive pressure generated by the eccentric mechanism in actuating the punch to perform the drawing operation. The use of the drawing press open at both sides,

as described, has enabled the press to be continuously operated, the crew of expert pressmen having ample time to feed a blank into the press for the drawing operation and 5 to remove the flanged bar therefrom, during the retraction of the drawing head in the cycle of movement of the latter. This last described construction of press has increased very materially the production of 10 the constantly operated open-side drawing press, as compared to that of the open-end, intermittently operated drawing press of the older type.

For several reasons it has been found desirable 15 to locate the operating mechanism of the drawing press below the floor line with reference to which the press is set. This more modern construction of drawing presses eliminates the crown piece with its 20 supporting end frames or fixed straining rods, and provides a most efficient means for lubricating such mechanism by means of a constant shower or spray of oil which falls upon the operating shafts, gears and cams. 25 In addition, the height of the press is correspondingly reduced, and only the bed and the reciprocating drawing head, together with the vertically movable straining rods which carry the latter, are visible above the 30 floor line.

My improved drawing press embodies in its construction the desirable features residing in both forms of the older types of presses, in that I am enabled to build an open-side 35 press, and at the same time secure the strength of construction which follows the use of distributed straining rods which carry the expansive force generated in the operation of the press. In constructing my 40 improved press, the bed thereof has a width sufficient to receive a matrix placed outside of the parallel rows of straining rods, and the reciprocating die carrying cross head carried by the straining rods has a width 45 corresponding to that of the bed of the press. In the preferred construction, the rows of straining rods are separated as in the first type of press described, by a space which will receive a third matrix and its complementary die member.

It is my purpose to employ the open-side 55 construction in drawing flanged bars of lesser length, and such as will not require the full expenditure of the power of the press. Crews of pressmen may work at each side of the press, which will be continuously operated. My purpose in providing the central arrangement of die members is to enable the press to be employed in the production 60 of side bars of a length exceeding that of the press, and which require a second operation to complete their formation. I propose also to use this central arrangement in the production of heavier flanged bars from 65 blanks of such gage as to more nearly approach

the compressive force of the press. In using the central set of die members, the press will be intermittently operated, if the blanks be fed and the flanged bars be removed manually.

In the older type of drawing presses, that first described by me, the punch carrying head was actuated by a single eccentric shaft, the thrust of which was resisted by the crown piece of the press. At the time 70 that the rotating eccentrics reached the position of their greatest outward throw, an angular pressure was developed by the drawing head bearing against the straining rods in the direction of the thrust of 75 the eccentrics, and a violent rocking strain was imparted to the press structure. It was therefore difficult to give a parallel motion to the drawing head, and the straining rods were subjected to greatly increased friction. 80

In place of the single eccentric shaft heretofore generally used, I propose to employ a pair of parallel eccentric shafts, arranged at the sides of the longitudinal center line of the press, and to gear such eccentric shafts 90 so as to rotate them synchronously and thus impart a parallel motion to the drawing head during its entire reciprocation. The arrangement of the dies on the face of the drawing head without regard to the longitudinal center line thereof, does not disturb such parallel motion, the pressure of the eccentrics upon the drawing head in my preferred construction being evenly distributed. In my modified construction of drawing 95 press, open at both sides, the pressure is equalized when both sets of die members are effective and operating.

In the drawing which forms a part of this specification,

Figure 1 is a view in elevation, partly broken at one end, showing my improved press.

Fig. 2 is a vertical section on the line 2—2, Fig. 1, showing the construction and arrangement of the parts.

Fig. 3 is a vertical sectional view showing a modification of the invention, but preserving the desirable feature of the open-side press and the parallel plural eccentric 110 motion for actuating the reciprocating cross head.

In the drawing, the base of the press is indicated by the letter A. This base will be placed in a suitable pit with the top thereof at or near the floor line. The bed B of the press is mounted on the base, as indicated. Parallel eccentric shafts C are journaled in the base at each side of the longitudinal center line of the press, each of such 120 eccentric shafts carrying gears c, the gears on one shaft intermeshing with the gears on the other; so that the said eccentric shafts are rotated synchronously in opposite directions. A lay shaft c¹ journaled at one side 125

of the base, is provided with pinions c^2 which engage the gears on one of the eccentric shafts, and thus transmit a movement of rotation to the eccentric shafts.

5 Straining rods D, arranged in spaced parallel rows, are guided in vertical openings formed in the bed of the press, each row comprising a plurality of rods. A reciprocating punch carrying cross head E is attached to the upper ends of the straining rods. The lower ends of the opposite rods in the two rows are connected by means of a cross head F, in such manner that the cross heads E and F and the straining rods D 5 comprise a frame movable as a whole and guided in its vertical reciprocations by the openings in the bed of the press, and in which the said straining rods have their bearings. Each gear c is flanked by an eccentric c^3 , and eccentric links c^4 connect the eccentrics c^3 with the lower cross heads F at the pivotal points c^5 .

6 The arrangement of gears, eccentrics, straining rods and connections to the head E, will be duplicated in the number necessary to properly equip a press of predetermined dimensions, so that such press will embody a structure possessing the requisite degree of resistance and strength, to enable 10 it to withstand the strains to which it is subjected while in operation.

Viewing Fig. 2, it will be observed that the straining rods arranged in parallel rows are spaced so that the pressure of the drawing head E, generated in the operation of the eccentrics, is divided equally between the two rows of straining rods, and that the said head E has a parallel motion with an even distribution of the pressure over its lower or 10 acting surface. In view of the parallel motion possessed by the head E, it is not material to the successful operation of the press, that the die members mounted upon the bed and upon the coöperating head be arranged 15 with any regard to the equalization of the pressure exerted by them. The jointly operating eccentrics, in the construction illustrated, act with a direct pull upon the head E, in which movement the tension is equally 20 distributed through the straining rods of both rows. The result of this equalized movement is to relieve the straining rods from the side thrust and from the increased frictional contact to which they have been 25 subjected in the older types of drawing presses, in which the drawing head was actuated from the eccentrics on a single shaft.

With the above described arrangement of the rows of straining rods, there is reserved 30 upon the bed of the press at the outside of each row a space on which may be placed a matrix or other die member, with a corresponding space upon the coöperating face of the drawing head, for the complementary die member. This construction enables me to

produce a drawing press which is open at both sides, and to realize the benefits which flow from the use of open side presses, in that the feeding of blanks to the press and the withdrawal of the drawn flanged bars therefrom may be performed with greater facility. As a consequence of this construction and arrangement, the output of the press is materially increased over the possible production of older forms of presses in which the time-consuming feeding and withdrawing operations were performed at the ends of the press. As stated at the commencement of this specification, it is my purpose to utilize the side feeding features of my improved press in the production of flanged bars and other parts of smaller dimensions. A gang of pressmen will work at each side of the press, and in view of the facility with which the operations of feeding and positioning the blanks and withdrawing the flanged bars from the press will be performed, the press will be constantly operated.

The press is also constructed with provisions for turning out work of a heavier class, and also bars having a length exceeding that of the press, and in which a second operation is necessary to the completion of the bar. I achieve this by arranging a set of die members for the bed B and head E, in the space defined by the straining rods. In this arrangement the blanks will be fed from one end of the press and removed from the other, upon the completion of the drawing operation. Unless automatic means be provided for so feeding the blanks and removing the bars, it will be necessary to operate the press intermittently at such times.

Fig. 3 shows a modified construction of press in which the very desirable feature of the open side press is preserved, and in which a parallel motion is imparted to the drawing head by means of parallel eccentric shafts as before described. However in this construction, a single row of straining rods D¹ is employed to connect the drawing head E¹ with the cross head F¹, which latter is actuated by a direct thrust of the 110 jointly operating eccentrics, instead of the draft of the eccentrics as in Fig. 2. In this construction, the head E¹ bears with an equalized and distributed pressure, and the straining rods are likewise relieved of the increased frictional engagement with their 120 bearings in the bed, resulting from the angular thrust of the eccentrics carried by the single shaft of the presses of the older type.

A very desirable result of the arrangement of the principal operating elements of the press below the floor line, is that which permits the operating mechanism to be efficiently lubricated by a constant shower of 130

spray of oil. The oil dripping from the mechanism may be collected and filtered for further use.

While I have described my invention as being embodied in a drawing press, it will be understood that the invention is not to be limited to the use stated, but that the press may be equipped with suitable dies which will punch contoured blanks from sheet metal plates, as well as for the production of other articles.

Having thus described my invention, what I claim and desire to secure by Letters Patent of the United States, is:

- 15 1. In a drawing press, a bed and a reciprocating head upon which the complementary die members of the press are mounted in a plurality of sets, actuating means for imparting a parallel motion to said members with respect to each other, and straining rods dividing the area of the bed and head into spaces for the reception of the die members of each set.
- 20 2. In a drawing press, a bed and a reciprocating head upon which the complementary die members of the press are mounted in a plurality of sets, parallel eccentric shafts and connections therefrom to the head to impart a parallel motion thereto, and straining rods embraced in such connections and dividing the area of the bed and head into a plurality of spaces for the reception of the die members of each set.
- 25 3. In a drawing press, a bed and a reciprocating head upon which the complementary die members of the press are mounted in a plurality of sets, parallel eccentric shafts and connections therefrom to the head to impart a parallel motion thereto, and straining rods constituting a part of such connections and arranged in parallel rows to divide the area of the bed and head into a plurality of spaces for the reception of the die members of each set.
- 30 4. In a drawing press, a bed and a reciprocating head upon which the complementary die members of the press are mounted in a plurality of sets, parallel eccentric shafts and connections therefrom to the head to impart a parallel motion thereto, and straining rods guided in the bed of the press and dividing the area of the bed and head into open spaces at each side of the press for the reception of the die members,

and render the die members accessible from both sides to facilitate feeding and withdrawal of the work, said straining rods forming a part of the connections to the reciprocating head.

5. In a drawing press, a bed and a reciprocating head, each supporting the complementary members of a plurality of sets of work shaping dies, straining rods connected to the head and guided in the bed and separating the die members of one set from those of another, and actuating mechanism for the head and connected thereto by the straining rods.

6. In a drawing press, a bed and a reciprocating head, straining rods attached to the head and guided in the bed to provide open spaces at each side of the press to facilitate feeding and withdrawal of the work at both sides of the press, and means for actuating the head through the straining rods.

7. In a drawing press, a bed and a reciprocating head, each supporting the complementary members of a plurality of sets of work shaping dies, parallel rows of straining rods connected to the head and guided in the bed whereby the area of the bed and head is divided into a plurality of spaces for the reception of the die members of each set, the spaces at the outer sides of the rows of straining rods constituting openings which enable the press to be fed from either side, and the interior space defined by the said rows of straining rods constituting an opening through which the press may be fed from the end, and means for actuating the head through the straining rods.

8. A drawing press comprising a bed and a head supporting the complementary members of a plurality of sets of dies of the press, and straining rods by which the head is guided, said straining rods dividing the area of the bed into a plurality of spaces opening at both sides of the press for the reception of the die members and for side feeding purposes.

In testimony whereof, I have signed my name at Canton, Ohio, this 18th day of May, 1920.

GEORGE M. SMITH.
